UNITED STATES PATENT OFFICE.

HARRY J. CRINER, OF DAVENPORT, IOWA, ASSIGNOR OF ONE-HALF TO ARTHUR G. BUSH, OF DAVENPORT, IOWA.

CLOTHES WRINGER.

Application filed January 24, 1922. Serial No. 531,362.

To all whom it may concern:

Be it known that HARRY J. CRINER, a citizen of the United States, residing at Davenport, in the county of Scott and State 5 of Iowa, has invented certain new and useful Improvements in Clothes Wringers, of which the following is a specification.

My invention relates to improvements in clothes wringers in which a pair of rubber 10 rolls under spring pressure is used to press the water out of the clothes passing between them.

The objects of my invention are, first, to provide a quick-acting release mechanism to 15 release the pressure of the rolls; second, to provide a simple, quick-acting lever to replace the pressure upon the rolls after it has been released; third, to provide a single adjusting apparatus which will adjust the 20 pressure at both ends of the rolls at the same time; fourth, to combine all of the above functions with a single operating lever; fifth, to provide as an article of manufacture, a simple, easily operated, inexpensive 25 apparatus for accomplishing the objects aforesaid.

I attain these objects by the mechanism illustrated in the accompanying drawing, in which—

30 Figure 1 is a front elevation of the upper part of a wringer embodying my invention showing the right hand portion of the frame in section upon the line RR of Figure 5; Fig. 2 is a plan view, but showing a portion of the frame cut away to disclose guide lugs or ears upon the sliding block; Fig. 3 is a detail partly in section showing the fulcrum block; Fig. 4 is a detail of the middle portion of the top frame; Fig. 5 is 35 a vertical cross section on the line SS of Figure 3, but showing the sliding and fulcrum blocks in full lines and the ball head and adjusting thread partly in dotted lines.

Similar numerals refer to similar parts 40 throughout the several views.

My invention comprises a frame, 3, of metal, preferably rust proof. For simplicity, I have shown only the upper portion of the frame, the lower portion of which may 45 be in any of the usual forms and secured to tub or washing machine in any suitable manner.

The rolls, 16 and 17, are mounted in the 50 frame in any of the usual wellknown bearings and operated by a drive shaft, 15,

which may be driven by hand or power as desired. The top of the frame is formed with a longitudinal opening at the middle portion, and a compression spring, 11, is mounted in the frame above the rolls, having blocks, 18, secured at each end which bear upon the upper roll.

A fulcrum block, 10, is mounted upon the spring at the middle thereof and secured in place by a set screw or pin, 22. The upper portion of the fulcrum block is chambered to seat a ball head, 9, formed at the lower end of the lever shaft, 14.

A sliding block, 2, is threaded upon the lever 14, and has ears or lugs, 5, projecting 70 therefrom which are adapted to slide on the under side of the flanges, 4, of the frame, 3.

The flanges, 4, project inwardly from the web, 6, of the frame, 3, and are formed integral therewith.

The sliding block, 2, is held against upward motion by the flanges, 4, and against downward movement by being threaded upon the lever shaft, 14. A handle, 1, is secured upon the upper part of the lever shaft, 14, by a pin, 1^a, or other suitable means.

A notch, 7, is formed at the middle of each flange, 4, which forms a detent for 85 the ears or lugs, 5.

The handle, 1, is preferably a little smaller than the width between the openings of the flanges 4, of the top frame so that it can be assembled by pushing it up 90 through the opening after the sliding block, 2, and the fulcrum block, 10, have been placed upon the lever shaft, 14. The ball head, 9, is then locked in its seat in the fulcrum block, 10, by the insertion of the 95 spring bar, 11, in the block, 10.

In the operation of my device, the tension is adjusted by screwing the handle, 1, down upon the threaded shaft, 14, forcing the ball head downward upon the spring, 11, in the 100 seat formed in the block, 10, until the desired pressure is exerted upon the upper roll, 17. The wringer is then operated in the ordinary way.

In case the clothes begin to wrap around 105 the roll or a hand is caught in the wringer, the pressure may be instantly released by striking the handle, 1, and moving it longitudinally of the frame.

The block, 2, will slide along between the 110

flanges, 4, and the ears or lugs, 5, will be unseated from the detent, 7, and slide along the lower side of the flanges, 4. This will allow the spring, 11, to rise and release all pressure upon the roll, 17.

When desired to resume operation of the wringer, the tension can be replaced by simply grasping the lever handle, 1, and returning it to its original position, the 10 length of the leverage and the shape of the flanges, 4, being such as to allow a person of ordinary strength to replace the lever in position without undue strain.

I claim:

15. 1. In a clothes wringer, the combination of a frame, wringer rolls mounted in said frame, a compression spring bar above said rolls, said frame having flanges extending along the top thereof and having a slot 20 between them, a block movable along said slot having lugs extending beneath said flanges, the latter being provided with notches in which said lugs seat and a lever having one end secured to a fulcrum on said 25 spring bar and extending through said block and provided with a handle.

2. In a clothes wringer, the combination of a frame, wringer rolls mounted in said frame, a compression spring bar above said 30 rolls, said frame having flanges extending along the top thereof and having a slot between them, a block movable along said slot having lugs extending beneath said flanges, and a lever having one end secured 35 to a fulcrum on said spring bar and extending through said block and provided with a handle.

3. In a clothes wringer, the combination

with a frame, of a longitudinal opening in the top thereof, with flanges formed upon 40 the sides of the frame and projecting inwardly toward the opening, a pair of rolls rotatably mounted in the frame, a pressure bar mounted in the frame above the rolls, a fulcrum secured upon the pressure bar 45 near the middle thereof, a block slidably mounted upon the flanges, a handle united with a bar mounted in the block and having its lower end seated in the fulcrum on the pressure bar.

4. In a clothes wringer, the combination of a pair of rolls mounted in a frame, a pressure bar mounted above the rolls, a lever having its lower end fulcrumed upon the pressure bar near the middle thereof and its upper end provided with a handle, and movable lengthwise in a slot formed in the top of the frame, a flange formed upon the frame on one side of the slot, a block secured to the lever and means united to the block 60 to engage the flange.

5. In a clothes wringer, the combination of a pair of rolls mounted in a frame, a pressure bar mounted above the rolls, a lever having its lower end fulcrumed upon the 65 pressure bar near the middle thereof, a block threaded upon the lever and longitudinally movable in a slot formed in the top of the frame, flanges formed upon the frame adjacent the slot, lugs united to the 70 block and adapted to engage the flanges, manually operable means secured to the top of the lever for turning it in the block.

In testimony whereof I affix my signature.

HARRY J. CRINER.
